UNITED STATES PATENT OFFICE.

GOTTFRID S. ELMQUIST AND CHARLES L. ELMQUIST, OF RAMSEY COUNTY, MINNESOTA.

CABINET.

1,056,158.

Specification of Letters Patent.

Patented Mar. 18, 1913.

Application filed October 6, 1911. Serial No. 653,252.

To all whom it may concern:

Be it known that we, GOTTFRID S. ELMQUIST and CHARLES L. ELMQUIST, citizens of the United States, residing in Ramsey county, in the State of Minnesota, have invented new and useful Improvements in Cabinets, of which the following is a specification.

Our invention relates to improvements in cabinets. Its object is to provide a novel and efficient cabinet having a plurality of movable compartments or containers accessible through an opening or openings in a wall of the cabinet and adapted to register with said opening or openings.

In the drawings, Figure 1 is a perspective view of our improved cabinet, Fig. 2 is a side elevation of the same with one of its end walls and a portion of the supporting wheel broken away, Fig. 3 is a rear view of our cabinet opened to show its interior mechanism, Fig. 4 is a detail view showing the link connections between the containers and Fig. 5 is a perspective view in detail showing one end of the operating bar with its contact spring and guide.

Referring to the drawings, we have used the reference numerals 10, 11, 12 and 13 to indicate respectively the front and rear walls, 30 ends and floor which form the cabinet structure. The supporting wheel 74 is provided with a shaft 15 mounted in the bearings 16 and 17 within the cabinet. The stub shafts 18 are equally spaced on the front face of the wheel 14 and are provided with bearings 19, which are bolted or otherwise attached to the upper ends of the containers 20, thus forming a construction by which said compartments or containers are pivotally suspended in upright positions. We provide openings 21 in the front wall 10 of the cabinet adjacent to the path of said containers. These openings are arranged to permit access to a pair of oppositely arranged containers. Vertically sliding doors 22 having spring lifts 23 and latches 24 of common construction form closures for said openings 21.

We have provided the following mechanism for rotating the supporting wheel 14 and for automatically stopping and locking the same when the containers reach positions registering with the openings 21. The motor 25 is mounted on the floor 13 of the cabinet and rotates the wheel 14 through the speed reducing pulleys 26 and 27 which

are respectively connected by the belts 28 and 29 to said wheel 14 and the motor driving pulley 30. The rear face of the wheel 14 is provided with a plurality of equally spaced perforations 31. Each of said perforations is provided with a shock absorbing bumper 32 on one side and a groove 33 on the other side leading thereto, said grooves being formed with beveled bottoms sloping inwardly from the face of the wheel. The operating bar 35 pivotally mounted on the bracket 34 is provided at its upper end with a lug 36 and at its lower end with a contact spring 37, said spring being arranged to move within the insulated guide 38 and adapted to contact with the motor terminal 39 at the end of said guide. The spring 40 connected at one end to the bracket 34 and at its other to the bar 35 causes the lug 36 to bear against the rear face of the wheel 14. The lug 36 normally impinges against the face of the wheel 14 and as said wheel revolves passes over the beveled bottoms of the grooves 33 to the perforations 31 which receive said lug to lock the wheel. The bumpers 32 deaden the impact between said lug and wheel. The perforations 31 are arranged so that when the wheel 14 is locked, two of the containers 20 will register with openings 21. A source of current, which may be a storage battery 41, or other source of electric energy, is supplied, one terminal 42 being connected by the wire 43 to the motor terminal 44, the other terminal 45 by the wire 46 to the bar 35. When this bar is in position with the lug bearing against the rear face of the wheel 14 the spring 37 rests in contact with the motor terminal 39, thus completing the circuit and causing the rotation of the wheel 14. When one of the grooves 33 reaches the lug 36 the bar 35 is operated by the spring 40 to hold said lug in the groove and to break the contact between the spring 37 and the terminal 39, thus disconnecting the motor 25 from the battery 41. The momentum of the moving parts causes the wheel 14 to continue to revolve until the lug 36 enters a perforation 31, and locks said wheel. The rod 47 having a push button 47a at its end, operates the bar 35 against the action of the spring 40 to remove the lug 36 from the perforations 31 and bring the spring 37 into contact with the terminal 39, thus releasing and starting the rotation of the wheel 14.

The links 48 connect the containers 20 for

the purpose of tying them together and minimizing their oscillation. Said links are pivotally attached at their ends to corresponding points on the faces of the containers near the bases thereof. This arrangement causes the containers to maintain a substantially upright position at all times. It will be observed that we have so arranged the links 48 that they do not obstruct the openings 21 in the front wall of the cabinet when the wheel is at rest and containers are presented to said openings 21.

We provide a stationary compartment 49 in the front of the cabinet. This compartment has a closure 50 like the doors 23 above described. Swinging doors 51 are arranged in the rear wall 11 of the cabinet, and open into the interior thereof. A desk 52 may form a working table for use with the cabinet proper.

In use the doors 22 are raised to permit access, through the openings 21 to the containers 20 and said containers are moved step by step and presented before the openings 21 by successive manipulations of the push button 47.

We have shown two openings in the front wall of the cabinet for the purpose of giving access to more than one container at a time. It is obvious however that without departing from the spirit of the invention more or less openings may provide access to more or less containers.

What we claim as new and desire to protect by Letters Patent is:

1. In a device of the class described, a cabinet having openings therein, closures for said openings, a revoluble support within the cabinet, containers pivotally suspended from said support, a motor for rotating the support, a stationary mounting within said cabinet, a stop on said mounting adapted to cut out said motor and lock said support in positions registering a container with each opening, and means for releasing said support.

2. In a device of the class described, a cabinet having openings therein, closures for said openings, a revoluble support within the cabinet, containers pivotally suspended from said support, a motor for rotating the support, a stationary mounting within said cabinet, a stop on said mounting adapted to halt said motor and lock said support in positions registering a container with each opening, and means for releasing said support.

3. A cabinet having a support revolvably mounted therein, a motor in operative connection with said support, a source of electric current connected with said motor, a stationary mounting within the cabinet, a

stop on said mounting for locking said support and disconnecting said motor from said source of current and a push rod for operating said means whereby the support is released and the motor connected with the source of current to rotate said support. 65

4. In a device of the class described, a cabinet having openings therein, closures for said openings, a revoluble support within the cabinet, containers pivotally suspended from said support, links attached to and connecting said containers, a motor for rotating the support, a stationary mounting 75 within said cabinet, a stop on said mounting adapted to halt said motor and lock said support in positions registering a container with each opening, and means for releasing said support. 80

5. In a cabinet, a revoluble supporting wheel therein having perforations in its face, a driving motor in operative connection with said wheel, a spring actuated bar pivotally mounted in said cabinet, a source of current connected with said motor and bar, a contact plate in the motor circuit, a contact spring on the bar adapted to engage and disengage said plate whereby the circuit through the motor is completed and broken, 90 a lug on said bar, said perforations being adapted to receive said lug for locking the wheel, and permitting the movement of the bar to disengage said spring and plate, shock absorbing bumpers adjacent to said perforations, a push rod for operating said bar to remove said lug from said perforations and engage said spring and plate. 95

6. In a cabinet a revoluble support therein having perforations in its face, a driving 100 motor in operative connection with said wheel, a spring actuated bar pivotally mounted in said cabinet, a source of current connected with said motor and bar, a contact plate in the motor circuit, a contact spring 105 on the bar adapted to engage and disengage said plate whereby the circuit through the motor is completed and broken, a lug on said bar, said perforations being adapted to receive said lug for locking the wheel and permitting the movement of the bar to position 110 disengaging said spring and plate, a push rod for operating said bar to remove said lug from said perforations and engage said spring and plate. 115

In testimony whereof, we have signed our names to this specification in the presence of two subscribing witnesses.

GOTTFRID S. ELMQUIST.
CHARLES L. ELMQUIST.

Correction in Letters Patent No. 1,056,158.

It is hereby certified that in Letters Patent No. 1,056,158, granted March 18, 1913, upon the application of Gottfrid S. Elmquist and Charles L. Elmquist, of Ramsey County, Minnesota, for an improvement in "Cabinets," an error appears in the printed specification requiring correction as follows: Page 1, line 31, for the reference-numeral "74" read *14*; and that the said Letters Patent should be read with this correction therein that the same may conform to the record of the case in the Patent Office.

Signed and sealed this 22nd day of April, A. D., 1913.

[SEAL.]

C. C. BILLINGS,

Acting Commissioner of Patents.
